OHIO.

SEWER-PIPE DIE.

SPECIFICATION forming part of Letters Patent No. 738,913, dated September 15, 1903.

Application filed June 5, 1903. Serial No. 160,162. (No model.)

To all whom it may concern:

Be it known that we, THOMAS W. JONES and CHARLES F. KANAER, citizens of the United States, residing at New Philadelphia, in the county of Tuscarawas and State of Ohio, have invented certain new and useful Improvements in Sewer-Pipe Dies; and we do hereby declare that the following is a full, clear, and exact description of the same, reference being had to the annexed drawings, making a part of this specification, and to the figures of reference marked thereon, in which—

Figure 1 is a vertical section showing a portion of the upper cylinder and illustrating the position of the core with reference to the outer die-section, also showing the relative position of the hinge-section. Fig. 2 is a side elevation showing a sewer-pipe form and the hinged sections opened to release the same. Fig. 3 is a transverse section of the outer die, showing the hinged sections closed, but illustrating the same open in dotted lines. Fig. 4 is a view showing a portion of the hinged sections in proper relation to the outer die and illustrating the sections secured together.

The present invention has relation to sewer-pipe dies; and it consists in the different parts and combination of parts hereinafter described, and particularly pointed out in the claims.

Similar numerals of reference indicate corresponding parts in all the figures of the drawings.

The object of the present invention is to provide a die for forming sewer-pipe by which the socket end of the finished pipe is located at the top end of the pipe when it leaves the die proper. Heretofore it has been customary to form the socket end of the die of the pipe upon the lower end, and when sewer-pipes are so formed it is necessary to turn them end to end, so that during the time they are being dried they will stand upon their non-socket ends. This is necessary in order to prevent injury to the socket, owing to the fact that when the pipe-section rests upon its socket end while in a plastic state it is liable to injure the socket to such an extent that it becomes difficult to enter the non-socket end of a pipe-section designed to be located in the socket.

In the accompanying drawings, 1 represents the upper cylinder, which is constructed in the ordinary manner and is of course provided with an ordinary plunger for forcing the plastic clay downward and is provided with the usual spider for suspending the core 2 by means of the supporting-head 3. The upper or plunger cylinder and means for supporting the core 2 form no particular part of the present invention; but said parts are common to sewer-pipe machinery of the class to which the present invention pertains.

To the bottom or lower end of the cylinder 1 or its equivalent is attached the outer fixed die 4, which is preferably tapered from its upper end downward and its inner diameter corresponding with the outer diameter of the finished sewer-pipe. The die 4 is provided with the lateral extending flange or ear 5, which ear forms a support for the hinged die-sections 6 and 7. Said hinged sections are semicircular, and when brought together at their free ends they constitute the lower die-section, located just below the lower end of the die-section 4. The hinged members 6 and 7 constitute that portion of the die proper which forms the socket end of the finished pipe. The inner faces of the semicircular hinged die-sections 6 and 7 are formed of a shape to correspond with the shape of the outer periphery of the sewer-pipe, and the lower portion of the core 2 is formed of a shape to correspond with the inner periphery of the finished sewer-pipe. The hinged sections 6 and 7 are provided with the inward-projecting flanges 8 and 9 and the core with the outward-extending flange 10, said flanges being so located with reference to each other that as the plastic clay is pressed or forced downward the portions of the clay located between the flanges 8, 9, and 10 will produce the socket end of the pipe and the portion of the pipe located below said flanges will constitute the straight portion of the pipe.

In the formation of sewer-pipe it is necessary to provide a follower, such as 11, which follower is counterbalanced in the ordinary manner, and when no weight is upon the follower its normal position is in close proximity to the lower end of the core and the bottom or under edges of the hinged die-sec-

tions 6 and 7; but as the pipe is formed the follower moves downward with the downward movement of the plastic clay until a pipe of the sufficient length is formed, after which 5 the plunger is stopped in the usual manner and any further downward movement of the follower 11 will sever the top or upper end of the pipe from the plastic clay located between the die 4 and the core 2 within said die 10 4, and in order to cause the pipe to be severed at the proper place the inward-extending flanges 12 and 13 are provided, the flange or rib 13 being located upon the core 2 and the flange or rib 12 upon the inner bottom 15 portion of the die 4, by which arrangement a narrow strip of plastic clay is located between the flanges or ribs 12 or 13, and of course there being less material at this point the pipe will be severed just at the point 20 where the flanges or ribs 12 and 13 are located. After the pipe has been severed from the main body of the plastic clay the pipe is finished and stands upon the follower 11, with the socket end up and in condition to 25 be removed for the purpose of drying.

It is well understood that in the manufacture of sewer-pipe that it is difficult to turn the finished sections upside down without injuring the contour of the pipe-section; but 30 by our peculiar arrangement the necessity of turning the finished pipe upside down is done away with.

It will be understood that when the sewer-pipe section is being formed the hinged die-sections 6 and 7 should be secured together at their free ends, which may be done in any mechanical manner. We have, however, 35 illustrated the hinged die-section 6 provided with a tenon 14 and the hinged die-section 40 7 provided with the slotted ear 15, said parts being so located that when the die-sections 6 and 7 are brought together the tenon 14 will enter the slot 16, after which the key or wedge 17 can be placed through the slot 18. 45 It will be understood that in order to release the socket end of the pipe the hinged die-sections 6 and 7 must be separated, so as to free the pipe, and when so separated the pipe is free to drop or move downward and away 50 from the forming-dies and core without injury to the pipe.

It will be understood that the hinged die-sections 6 and 7 should move in a true horizontal plane, and in order to prevent any 55 sagging of the hinged die-sections at any point within the limits of its movements, the segmental arms 19 are provided, which segmental arms are preferably formed integral with the die 4.

60 For the purpose of properly supporting the hinged sections 6 and 7 they are each pro-

vided with the ears 20, to which ears are attached the bars or yokes 21. The top or upper ends of the bars or yokes are provided with the antifriction-rollers 22, which anti-friction-rollers travel upon the upper edges of the segmental arms 19.

For the purpose of limiting the outward movement of the hinged die-sections 6 and 7 the segmental arms 19 are provided with the 70 stops 23, which stops are preferably located at the outer ends of the segmental arms, as illustrated in Fig. 2. For the purpose of limiting the inward movement of the hinged die-sections 6 and 7 they are each provided 75 with the shoulders 24, which shoulders strike against the flange 25, formed upon the bottom end of the die 4, by which arrangement the hinged die-sections are brought into proper position and their inward movement 80 stopped at the proper point.

It will be understood that various sizes of dies and cores may be provided and must be provided to produce sewer-pipe of different diameters. It will also be understood 85 that the hinged sections 6 and 7 should be properly connected together by means of the hinged bolt 26, which hinged bolt passes through apertures formed in the ears 27 and 28, the ears 27 being formed upon one hinged 90 die-section and the ears 28 upon the opposite hinged die-section, thereby constituting an ordinary and common hinge, giving to each section 6 and 7 a common center.

Having fully described our invention, what 95 we claim as new, and desire to secure by Letters Patent, is—

1. The combination of a pipe-forming die having located therein a core, said core provided with an outward-extending flange, 100 hinged die-sections provided with inward-projecting flanges, beads formed upon the pipe-forming die, said beads located above the hinged die-sections, substantially as and for the purpose specified. 105

2. The combination of a pipe-forming die secured to a plunger-cylinder, said die supplied with segmental arms, die sections or members hinged to the pipe-forming die and provided with lugs, bars or yokes secured to 110 the lugs formed upon the hinged die-sections, substantially as and for the purpose specified.

In testimony that we claim the above we have hereunto subscribed our names in the 115 presence of two witnesses.

THOMAS W. JONES.
CHARLES F. KANAER.
